UNITED STATES PATENT OFFICE.

JESSE ALEXANDER, OF NEW YORK, N. Y., ASSIGNOR OF ONE-HALF TO THEODORE A. REED AND ONE-HALF TO WILLIAM GROSVENOR RIDGWAY, BOTH OF BROOKLYN, NEW YORK.

TYPE-WRITER-RIBBON MECHANISM.

1,039,473.

Specification of Letters Patent. Patented Sept. 24, 1912.

Application filed July 15, 1911. Serial No. 638,608.

To all whom it may concern:

Be it known that I, JESSE ALEXANDER, a citizen of the United States, and resident of New York, in the county of Kings and 5 State of New York, have invented certain new and useful Improvements in Type-Writer-Ribbon Mechanism, of which the following is a specification.

My invention relates to typewriting machines and is particularly concerned with 10 improvements in the ribbon mechanism thereof.

The invention has for its object to feed 15 the ribbon uniformly past the printing point during the printing operation, said feed being effected by the action of the type bars upon the usual universal bar.

A further object of the invention is to 20 provide means for readily reversing the ribbon feed, which means may be conveniently manually controlled.

A further object is to so construct such 25 ribbon reversing means that the ribbon spool from which the ribbon is to be fed will be relieved of pressure not only of the actuating pawl, but also of the spring or other means for preventing back-lash.

A further object is to provide for ready 30 removal of the ribbon spools.

With these objects in view, the invention consists in the construction and arrangement of parts, a preferred embodiment of 35 which is illustrated in the accompanying drawings, in which—

Figure 1 is a plan view of so much of a typewriting machine as is necessary to illustrate my invention. Fig. 2 is a front elevation of some of the parts shown in Fig. 1. 40 Fig. 3 is a sectional view on the line 3—3 Fig. 2, certain parts being omitted for clear illustration.

In the embodiment of my invention herein selected for illustration, 1 indicates the 45 machine frame having the usual type bar segment 2, to which the type bars 3 are pivoted in the slots 4. Upon either side of the machine and preferably in frame plates 5, as well as in the frame projections 6—6, are journaled ribbon spool shafts 7—7, each having a head 8 at its lower end below the bearing plates 6 and having a cross head 9 at the upper end, be-

tween which and the frame plate 5 a spring 10 is interposed to hold each of said shafts 55 in elevated position with the head 8 substantially against the frame plate 6. The heads 9 are provided with transverse ribs 11 adapted to take into corresponding slots 12 in the bottom of the hubs of the ribbon 60 spools 13. The upper ends of these hubs are also provided with recesses 14 adapted to engage small lugs 15 on bearing plate 16, whereby the spools may be removably attached to the actuating shaft 7 by merely 65 depressing the spools and shafts against the pressure of the springs 10 and thereupon slipping the spools from beneath the spool supporting arms 16. The ribbon may be guided from one spool to the other by any 70 suitable form of guide, as shown at 17.

In order to feed the ribbon from one spool to the other, each shaft 7 is provided with a ratchet wheel 18 adapted to be engaged by a pawl 19 having an upwardly 75 extending arm 20 adapted to be pivoted to a rock arm 21 fixed to the rock shaft 22 to which shaft also are fixed the arms 23 connected to the universal bar 24 by which the shaft 22 is rocked by each of the type bars 80 when moved to printing position. Upon return of the type bars, the universal bar resumes its normal position through any suitable form of spring, whereby the spool actuating pawl is impelled forwardly to drive 85 the spool with which it is in engagement.

In order to hold the pawl in effective engagement with the ratchet, each pawl is provided with a spring 25 which rests against one side of an aperture 26 of an upstanding arm or lug 27 mounted upon the manually operable reversing bar 28. This apertured lug 27 therefore serves both as a support and as a guide for the spool actuating pawls. In order to prevent back-lash 90 of the spool to which ribbon is being fed, a suitable spring 19' may be mounted upon the lug 27, which spring, when the pawl is in engagement with the ratchet also engages the same, and when the pawl is disengaged 95 from the ratchet by the ribbon reversing mechanism this spring is simultaneously released to permit of ready feed of the ribbon from the stored spool. In order to effect this reversing movement or feed, the bar 28 100 is slidably mounted upon a suitable portion

105

of the machine frame by means of the screws 29 engaging slots 30 in said bar, and each end of the bar is preferably provided with a finger piece 31 for convenient operation.

- As will be seen from an inspection of Figs. 1 and 2, the shifting of the bar from right to left will, through the apertured lugs 27, cause one of the pawls and its back-lash spring to engage the adjacent spool and simultaneously disengage the opposite pawl and its spring from its spool. In order to hold the reversing bar 28 in either of its shifted positions, I provided a bell-crank lever 32, one arm of which engages a pin 33 on the reversing bar, and the opposite arm is provided with the beveled faces 34 and 35 adapted to engage the friction roll 36 on a spring arm 37, suitably mounted on the machine frame 38. When the reversing bar is shifted to either of its operative positions, the roll 36 engages one of the faces 34 or 35 and holds said bar in such position.
- By the above described construction it will be seen that the ribbon spools may be readily mounted or removed from the machine, and that the ribbon feed may be readily reversed. It will further be seen that the ribbon operating mechanism includes few parts, and said parts have direct and effective connection with the actuating member, namely, the universal bar.

While I have herein described the particular embodiment of my invention, it is to be understood that the same may be altered in detail and construction of parts without

departing from the spirit or scope of my invention.

What I claim is:

1. In a typewriter ribbon mechanism, the combination with a pair of ribbon spools, operating shafts therefor and means for operating said shafts, of a supporting arm overstanding each spool, a yielding support 45 for each shaft whereby said shaft may be depressed and the spool disengaged from said arm and detached from said shaft.

2. In typewriter ribbon mechanism, the combination with a pair of ribbon spools, 50 actuating shafts therefor, operative connections for said shafts, a detachable connection between the end of each spool and its shaft, a supporting arm to hold the spool in engagement with its shaft, a yielding support 55 for said shaft whereby the shaft may be removed away from said arm and the ribbon spool removed therefrom.

3. In typewriting ribbon mechanism, the combination with a pair of ribbon spools of 60 actuating shafts therefor, means for actuating said shafts, said shafts being slidably and yieldably mounted in bearings, a supporting arm for each spool opposite each shaft and detachable connections between 65 said spool, said shaft and said arm whereby the spool may be removed by moving said shaft away from the coöperating supporting arm.

JESSE ALEXANDER.
